(Cl. D81—25)

FIG. 1

FIG. 2

FIG. 3

Fig. 1 is a perspective view showing the front and top of a recessed control panel for a cooking range or the like embodying our new design;

Fig. 2 is a top plan view thereof; and

Fig. 3 is a cross-sectional view taken on the line 3—3 of Fig. 2 to better show the configurational details of the panel and its elements.

The broken lines are included for illustrative purposes only.

We claim:

The ornamental design for a recessed control panel for a cooking range or the like, as shown and described.
